CLAIM

The ornamental design for an agricultural product skid for product applicator, as shown and described.

DESCRIPTION

FIG. 1 is an isometric view of an agricultural product skid for product applicator in accordance with the present invention;

FIG. 2 is a side elevation of a first side of the agricultural product skid for product applicator of FIG. 1;

FIG. 3 is a side elevation of a second side of the agricultural product skid for product applicator of FIG. 1;

FIG. 4 is a front elevation of the agricultural product skid for product applicator of FIG. 1;

FIG. 5 is a rear elevation of the agricultural product skid for product applicator of FIG. 1;

FIG. 6 is a top plan view of the agricultural product skid for product applicator of FIG. 1; and,

FIG. 7 is a bottom plan view of the agricultural product skid for product applicator of FIG. 1.

The broken line showing of a product applicator tank is included for the purpose of illustrating environmental structure only and forms no part of the claimed design.
